DES. 2223

Frederick Boshart of New York, N.Y.

Letters Patent No. 2,223. Dated Decr. 5, 1865.

Design for the Elbow of a Sheet Metal Pipe.

The schedule referred to in these letters Patent and making part of this same.

To all whom it may concern:

Be it known that Frederick Boshart of the City, County and State of New York, have invented a new and Original Design for the Elbow of Sheet Metal Pipes; and I do hereby declare that the following is a full, clear and exact description thereof, which will enable those skilled in the art to make and use the same, reference being had to the accompanying drawings, forming part of this specification, in which-

Figure 1 is a side view of an elbow showing my design.

Figure 2. a transverse section of the same taken on the line a—a fig. 1.

Similar letters of reference indicate corresponding parts.

The elbows of sheet metal pipes, especially stove pipes, are very generally placed in exposed positions, and, as at present constructed, are rather unsightly, and do not present a very ornamental appearance in a well furnished room. The object of this design is to add to the appearance of the elbow, so that it, and the pipe generally will not have that repulsive look that they now have.

A represents the elbow of a sheet metal pipe composed of a curve a, and two straight portions b, b. The curve a, is a quarter circle extending from 1 to 2, and the straight portions b, b are at the ends of the curve and at right angles to each other, as shown in fig. 1.

DES. 2223

The concave side or inner portion of the curve is embossed with a series of projections c. in relief, said projections having a radial position meeting if prolonged in a point d. which forms the centre of circles of which the outer and inner sides of the curve a. are portions, see fig.

The projections c. are at each side of the elbow of convex or rounded form transversely, of taper form longitudinally, gradually diminishing in width from their inner to their outer ends, conforming longitudinally to the cylindrical shape of the elbow, and rounded at their ends, extending about half way round the elbow, the other longitudinal portion of which has a plain or smooth exterior.

The curved or quarter circle elbow with its straight ends and projections at each side of its inner portion or longitudinal half constitute the design.

I claim therefore, as a new and desire to secure by letters Patent

The curved or quarter circle a. with its straight ends b. and the projections c. at each side of the inner portion or longitudinal half of the curve, all as shown and described from a new and original design for the elbow of sheet metal pipe.
